Application November 5, 1936, Serial No. 65,705

Term of patent 7 years

To all whom it may concern:

Be it known that I, Félicie Eugénie Amélie Wanpouille Bergaud, a citizen of the French Republic, and resident of 43 Boulevard Suchet, Paris, France, have invented a new, original, and ornamental Design for Mirrors or Similar Articles, of which the following is a specification, reference being had to the accompanying drawing, forming a part thereof:

Fig. 1 is a front elevational view of a mirror or similar article showing my new design;

Fig. 2 is a sectional view taken on line 2—2 of Fig. 1.

I claim:

The ornamental design for a mirror or similar article, as shown.
